UNITED STATES PATENT OFFICE.

FREDERICK SNOW, OF PERRY, IOWA, ASSIGNOR TO GLOBE MANUFACTURING COMPANY,
A CORPORATION OF IOWA.

GEARING.

1,156,377.

Specification of Letters Patent.

Patented Oct. 12, 1915.

Application filed March 17, 1913. Serial No. 754,685.

To all whom it may concern:

Be it known that I, FREDERICK SNOW, a citizen of the United States, and residing at Perry, in the county of Dallas and State of Iowa, have invented a certain new and useful Gearing, of which the following is the specification.

It is the object of the present invention to provide a laundry appliance for washing and rinsing clothes in an efficient and economical manner and more particularly to provide a structure adapted for power drive as from an electric motor or gas engine, the delivery of the power being easily controllable by the operator and certain of the parts being adjustable in position to facilitate their use.

In the embodiment here illustrated, the wringer is positioned on a supporting means, and the supporting means can be moved along the platform and in addition to this the wringer can be swung horizontally on one of the standards of the supporting means. Throughout all of these movements of the wringer, the driving connections to the source of energy may be maintained. There results from this construction the advantage that clothes can be wrung out of a washing machine tub into a rinsing tub and then can be wrung out of the rinsing tub into the bluing water and finally out of the bluing water into a basket, and all of these wringing operations can be carried out by the same wringer, driven from the same shaft and without shifting the positions of the several tubs and basket.

The embodiment here illustrated possesses other objects and advantages more particularly in respect to the arrangement of gearing and the mode of control as will be made clear by the following detailed description which is to be taken in conjunction with the accompanying drawings wherein—

Figure 1 is a side elevation of the complete construction showing the wringer positioned close up to the washing machine tub. Fig. 2 is an end elevation of the wringer supporting means illustrating some of the parts in section. Fig. 3 is a plan view of the same. Fig. 4 is a detail of the track whereon the wringer supporting means may slide. Fig. 5 is a section through the structure of Fig. 4 on the line indicated by the arrows. Fig. 6 is a detail of the reversible clutch mechanism whereby the direction of

rotation of the wringer rolls is controlled. Fig. 7 illustrates the driving clutch for the dolly, and Fig. 8 is a detail of the lid fastener used to control the dolly clutch.

The embodiment here illustrated comprises a platform 11 supported on suitable legs 12, with longitudinal cross bars 13, and lateral cross bars 14. The washing machine tub 15 is positioned on this platform and in the present instance, is located at one end 60 of the same, leaving a space suitable for holding a rinsing or bluing tub into which the clothes may be passed from the tub 15. Beyond this free space, the platform is provided with an extension platform 16 which 65 may be hinged to the end of platform 11 so that it can be folded over upon platform 11. When extended out into working position, the extension platform 16 rests on legs 17. This platform may be used for supporting a 70 basket or the like.

The tub 15 is provided with a hinged lid or cover 18 from which the dolly 19 is operatively supported as shown in dotted lines, Fig. 3. A power shaft 20 is suitably mounted 80 under the tub 15 and extends to the end of the platform. This power shaft may be driven from any suitable source of power as by means of the pulley 21. Loosely mounted on said power shaft is a spur gear 22. A sleeve 23 is suitably splined on shaft 20 to travel with the same, as shown in Fig. 7, and a clutch 24, is slidably mounted to establish a driving connection between sleeve 23 and gear 22, to rotate the same with the 85 power shaft. The clutch member 24 is actuated by a link 25 which is pivotally connected to the crank bend 26 of the dolly control rod 27. This rod 27 is journaled in bearings 28 and 29, and above these is 90 provided a shoulder 30 to rest on bearing 29. Above the shoulder is positioned a lug 31, which can enter a socket 32 in the handle member 33. When the lug is in the socket, turning the handle member 33 will turn the 100 rod 27 to throw the clutch member 23 into or out of driving engagement with the spur gear 22. The handle member 33 is carried by the cover 18 of the tub and has a projection 34 at its lower end, this being arranged to slide under plate 35 which is secured to the tub at and around the upper end of the rod 27. The arrangement of the projection 34 and plate 35 with respect to the socket 32 and the lug 31 is such that 105 110

when the projection 34 is under the plate 35, the cover is locked and the clutch member 23 is in engagement with the spur gear 22, but when the projection 34 is slid from under the plate 35, thereby allowing the cover to be raised, the clutch member 23 is slid out of engagement with the spur gear 22.

A driving gear 36 is suitably mounted in bearings 37 under the tub and in engagement with the spur gear 22. Pivoted to the face of the drive gear 36 is a link 38 pivoted at its other end to a lever 39 which is pivoted to the bracket 40 secured to the tub 15. A link 41 also pivoted at one end to this bracket 40 is pivoted at its other end to a pitman 42, and lever 39 is also operatively connected to said pitman 42 to move it back and forth as the gears rotate. This pitman 42 is pivoted to a rack bar 43 which is in engagement with a gear 44 housed in the upper face of the cover 18 and connected to the dolly 19. Thus the dolly 19 will be operated when the clutch 23 is set into driving engagement with gear 22 but will not rotate when the cover latch is open.

A support for carrying a wringer is mounted to slide along the platform 11. This support comprises two trucks 45 and 46 having grooves to engage tracks 47 provided along the sides of the platform. As shown in Figs. 4 and 5, the trucks have roller bearings above and below said track and have screw plugs 48 to hold the rollers in their sockets. A cross-piece 49 extends under the platform and connects the two trucks.

On truck 45 is mounted a bracket support having a vertical bar 50 and an inclined bar 51 connected together at their upper ends by a casting 52. On truck 46 is mounted a housing 53. A swinging bracket 54 on which a wringer frame 55 is secured has a socket to receive the upper end of the housing 53 so that the wringer frame may swing about housing 53 as a pivot. The free end of bracket 54 can be locked to the adjacent support by means of a latch 56, thus to hold the wringer in position for use at the side of the tub 15.

Two beveled gears 57 and 58 are loosely mounted on power shaft 20 and have their toothed sides facing each other. These beveled gears are held in constant engagement with a third beveled gear 59 by a bracket 60. Beveled gear 59 is fixed on a shaft 61, the outer end of which is provided with a worm 62, which is in engagement with a worm gear 63 secured to the lower end of a vertical shaft 64 mounted to rotate in housing 53.

To each side of bracket 60 on power shaft 20 is mounted a grooved sleeve 65 which is splined to power shaft 20. In the grooves of these sleeves 65, the bifurcated ends of a bracket 66 engage. To this bracket 66 is

pivoted a link 67 which is pivotally connected to the crank arm of a rod 68 journaled along the side of the tub 15 and extending through the casting 52 with a handle 69 secured above said casting 52.

Each of the beveled gears 57 and 58 have projections extending through the bracket 59, these being provided to engage corresponding orifices in the sleeves 65. When handle 69 is turned, its crank and link connection to bracket 66 will slide sleeves 65 to the left or to the right of bracket 60 so that either beveled gear 57 or beveled gear 58 can be rotated, or by putting the clutch in an intermediate position neither will be rotated.

At the upper end of shaft 53 is secured a beveled gear 70 which is in engagement with a beveled gear 71 secured to a horizontal shaft 72 which may be a horizontal extension of one of the usual wringer rolls 73 and 74. Thus it will be seen that when beveled gear 57 is engaged by sleeve 65, it will rotate shaft 61 in one direction and that in turn will rotate the wringer rolls, and when beveled gear 58 is engaged by sleeve 65, the wringer rolls will be rotated in the opposite direction.

From the description it will be seen, that the wringer frame and its supporting means can be slid the entire length of the platform. By means of the splined connection of the sleeves 65 on the power shaft 20, these sleeves will slide along with the wringer frame, and its supporting means and the wringer can be operated at any position along said platform. When the wringer is at the extreme end of the platform next to the extension 16, a tub can be placed on the platform and clothes wrung from the tub to a basket or the like positioned on the extension 16. It will also be seen that by means of the beveled gears 70 and 71 and the pivotal connection of the bracket 54 to housing 53, the wringer can be swung around horizontally to any position. If it should be swung around to the position indicated in the dotted lines in Fig. 3, clothes may be wrung from a tub on the platform 11 to a basket or other tub standing along side of the platform. Obviously a great variety of operative positions can be had by combining the sliding and swinging movements of the wringer.

While there is herein shown and described but one embodiment of the invention, it is to be understood that various changes and modifications may be made by those skilled in the art without departing from the scope of the invention as defined in the appended claims.

Having thus described my invention, what I claim as new and desire to secure by Letters Patent is:

1. In a mechanism of the class described,

the combination of a power shaft, gear mechanism driven by said shaft and movable along the same, an upright shaft controlled through said gear mechanism, a pair 5 of work shafts operatively connected to be driven by said vertical shaft, said work shafts adapted to swing about said upright shaft, said work shafts being movable into a new operative position when said gear mechanism 10 is moved along said power shaft.

2. In a mechanism of the class described, the combination of a platform, a power shaft supported under said platform from end to end, a pair of supports mounted to 15 slide along said platform, a vertical shaft journaled within one of said supports, reversible driving connections between said vertical shaft and said power shaft, and a pair of work shafts positioned above said 20 supports and movable therewith, said work shafts being driven by said vertical shaft and adapted to swing around.

3. In a mechanism of the class described, the combination of a platform, a pair of 25 trucks slidably mounted upon the platform, a support carried by each truck, a power shaft carried by the platform, a shaft journaled within one of the supports, clutch mechanism movable along said power shaft 30 with the supports, said clutch mechanism being operatively connected with the shaft carried by one of said supports, a pair of work shafts pivotally supported upon the support carrying the shaft and operatively 35 connected with the last said shaft for the purpose specified.

4. In a mechanism of the class described, the combination of a platform having rails 40 along its edges, supporting means mounted to slide along said rails, a vertical shaft carried by said supporting means, a frame positioned above said supporting means and having a pair of work shafts geared to said vertical shaft, a power shaft under said platform, and reversible clutch mechanism movable 45 along said power shaft and operatively connected with said vertical shaft to start or reverse said work shafts at the will of the operator.

5. In a mechanism of the class described, the combination of a platform having a track-way, supporting means mounted to slide along said platform, a frame carried by said supporting means, a pair of work 55 shafts in said frame, a vertical shaft movable with said supporting means and operatively connected with said work shafts; a horizontal shaft geared to said vertical shaft, a power shaft under said platform, and reversible clutch mechanism movable along said power shaft and operatively connected between said power shaft and said horizontal shaft to control the movement of the pair of work shafts.

6. In a mechanism of the class described,

the combination of a support, a vertical shaft carried by said support, a frame pivoted to swing with respect to said support, and a pair of work shafts carried by said frame and operatively connected with said vertical shaft, means for driving said vertical shaft, said support and its vertical shaft being movable horizontally into a new position while operative driving connections to said vertical shaft are maintained. 75

7. The combination of a platform, supporting means slidably mounted on said platform, a frame pivoted to swing with respect to said supporting means, a pair of work shafts carried by said swinging frame, 80 driving means for said shafts carried by said supporting means, and a power shaft operatively connected with said driving means irrespective of the position of said supporting means on its frame. 85

8. In a mechanism of the class described, the combination of a platform, supporting means movable along said platform, a vertical shaft carried by said supporting means, a frame pivoted to swing with respect to 90 said supporting means, a pair of work shafts carried by said frame and connected with said vertical shaft, a power shaft and connections between said power shaft and said vertical shaft, said connections being adapted to remain operative whether said supporting means is in one or another of its several positions on said platform. 95

9. In a mechanism of the class described, the combination of a platform, a power 100 shaft positioned under said platform and extending from end to end thereof, supporting means slidably mounted on said platform, a vertical shaft carried by said supporting means, a frame pivotally mounted to swing with respect to said supporting means, a pair of work shafts carried by said frame and operatively connected with said vertical shaft, and clutch mechanism 105 operatively connected between said power shaft and said vertical shaft and adapted to maintain operative driving relation therewith irrespective of the position of said supporting means along said platform. 110

10. In a mechanism of the class described, the combination of a platform having a track-way, supporting means movable along said platform, a vertical shaft carried by said supporting means, a frame pivoted to swing about said vertical shaft, a pair of work shafts carried by said frame and geared to said vertical shaft, a horizontal shaft movable with said supporting means and geared to said vertical shaft, a power shaft, and reversible clutch mechanism slidably mounted on said power shaft and adapted to establish driving connection with said horizontal shaft. 120 125

11. In a mechanism of the class described, the combination of a platform, supporting 130

means movable along said platform and having a pair of supporting standards, a frame pivoted to swing about one of said standards, a pair of work shafts carried by said frame, a vertical shaft carried by said last named standard and connected to one of said work shafts, a power shaft, clutch mechanism interposed between said power shaft and said vertical shaft, and clutch controlling means carried by the second standard of said supporting means, said

clutch controlling means being adapted to control the direction of rotation of said work shafts.

In witness whereof, I hereunto subscribe 15 my name to this specification in the presence of two witnesses.

FREDERICK SNOW.
